UNITED STATES PATENT OFFICE.

WILLIAM G. SIEBER, OF CHICAGO, ILLINOIS.

DISPLAY-COUNTER.

1,007,562.

Specification of Letters Patent. Patented May 18, 1914.

Application filed April 5, 1912. Serial No. 688,646.

Part of claim may concern:

It is known that I, WILLIAM G. SIEBER, a citizen of the United States, residing at Chicago, in the county of Cook and State of Illinois, have invented a certain new and useful Improvement in Display-Counters, of which the following is a specification.

My invention relates to improvements in display counters and the like, and is illustrated diagrammatically in one form in the accompanying drawings, wherein—

Figure 1 shows a part front elevation; Fig. 2 a section along the line 2—2 of Fig. 1; Fig. 3 a section along the line 3—3 of Fig. 2; Fig. 4 a detail elevation view of one of the bearings; Fig. 5 a section along the line 5—5 of Fig. 4; Fig. 6 a vertical section from one of the display pockets; Fig. 7 is a rear elevation of one of the pockets; Fig. 8 is a detail vertical section of a modified form of the display pocket along similar lines; Fig. 9 is a horizontal section looking down upon the counter; Fig. 10 is a section along the line 10—10 of Fig. 9.

Like parts are indicated by like letters in all the drawings.

The display counter A having the top A¹, sides A² and legs A³ together with the apertured front A⁴ contains the separate flat display pockets B. The pockets B are made up of each of the rectangular outer frame B¹, the bottom grooved member B² projecting inwardly from the rectangular frame, and the two grooved side members B³. The frame B¹ is recessed at B⁴ and this recess on the bottom alone is partially covered by the member B². The sliding transparent panel B⁵ fits within the recess and is held against inward displacement at its bottom by the member B⁶. The rear panel B⁶ is slidably mounted in any one of the slots or grooves in the bottom and sides and the sliding strip B⁷ slides, in the preferred form as indicated in Fig. 6, across the panels B⁶ and B⁸ and is wedged into the recess B⁴, thus pushing the panel B⁵ down into the recess at the bottom of the frame. The materials or objects to be displayed which are packed in the pocket, of course tend to resist any rearward movement

of the transparent panel, or even if such rearward movement does occur, the presence of the sliding strip prevents the panel being moved up out of the slot at the bottom and prevents the outflow of any material from the bottom of the pocket beneath the lower edge of the panel or window. In this form

of my device I rely upon the presence of the sliding strip to prevent the vertical displacement of the glass, but at the same time I rely upon the material in the pocket to prevent the horizontal displacement of it, particularly at the top, since at the bottom it is held against horizontal displacement by the groove in which it rests.

In the form indicated in Fig. 8, the recess in which the window B⁵ is located fits the window more closely especially at the top and there is no room for the strip to enter between the recess at the top and side, and here the presence of the strip operates to prevent a horizontal displacement of the window and the frame itself operates to prevent a vertical displacement. In both cases, however, the sliding strip is slidably mounted on the top of the inner opaque panel, and contacts or engages the upper edge of the transparent panel to hold it in position. The latch or finger piece B⁸ is pivotally mounted on the upper ends of the frame B¹ in opposition to the groove B⁹ in which the part B⁷ slides, and is adapted to close that groove and prevent the sliding displacement of the strip unless this piece is lifted out of the way by the operator. The removable pockets are each supplied at their bottom with the lug B¹⁰ located behind the frame and at the top are recessed as indicated at B¹¹ in the usual manner.

The counter A contains beneath the top A¹ and between the walls A² the sliding drawers C which are slidably mounted on the cross pieces or guide rails C¹. The guide rails or cross pieces C¹ contain the ball bearings which in one form as indicated in Figs. 2, 3, 4 and 5 are made up of flat metallic strips C² slotted as indicated at C³. These slots each contain the balls C⁴ which project a short distance through them above the surface of the strip and ride upon the channels C⁵ rigidly attached to the strips. These balls contact the lower edges of the drawer frames and permit the drawers to slide freely back and forth. In another and preferred form, however, of ball bearings as indicated in Fig. 9, the usual drawer C is mounted upon the guide rail D. This drawer has the side members D¹ downwardly projecting and shod with the metallic strips D². The runways D³ having the shallow grooved oval strips D⁴ contain the balls D⁵. These balls are held in position by the cap D⁶ which cap is cut away in such

maanner that on one side beneath the shoes D^a the balls are exposed, projecting up through the slots D^7 , whereas on the ends and on the other side the balls are contained 5 within the groove D^8 .

The operation of this device is quite obvious, in that when the drawer is drawn in one direction, the balls roll with it, passing around and around the track; and in the 10 other, the movement of the balls is reversed. At no time when the drawer is in motion do any of the balls stop, and they are free at all times to rotate between the shoe on the bottom of the drawer and the track.

15 It will be evident that while I have shown in my drawings an operative device, still a large number of changes, both with respect to the drawers, ball bearings, etc., and to the pockets themselves, and also with respect to 20 the general arrangement, size, etc., of the counter, might be made without departing materially from the spirit of my invention, and I wish therefore that my drawings be regarded as in a sense diagrammatic.

25 The use and operation of my invention are as follows: The separate pockets are assembled by first placing the glass front in position in such manner that it rests at the bottom in the slot formed by the groove in 30 the frame and the bottom wall. The window is held in position along the sides and at the top by resting within the recess in the frame. The sliding partition is then put into place. The pocket is then filled with 35 the objects to be displayed, which are packed closely down, compressing the transparent partition outwardly against the frame. In one form the sliding strip is then pushed in through the slot in the side 40 walls, sliding across the top of the opaque partition and holding it in position against vertical displacement and wedging into the space in the frame between the pocket and the top of the glass wall. The catches or 45 buttons are then turned around to hold this sliding strip in position. The window frame is thus effectually held against any vertical displacement, since it is wedged against the sliding strip, and the presence of 50 the material thus prevents any horizontal movement sufficient to permit the lifting of the window at the bottom and the escape of material. It is understood that the presence of this strip prevents a slight inward dis-

55 placement of the window from permitting it to be disengaged and this is important, in view of the fact that the materials packed in the pockets are always slightly compressible and if only the recess in the frame were

relied upon to hold the window against 60 displacement, when this compressibility is taken advantage of, then as soon as the window has gotten out of register with the frame, it will be free to move up, thus permitting the pocket to discharge its contents. 65 In the other form shown, the sliding strip is wedged against the back of the window and prevents, physically and positively, its being moved out of the recess, and the recess itself is so positioned and sized as to 70 hold the window against vertical displacement sufficient to free it at the bottom and permit the spilling of the contents. The drawers in the counter are located as indicated one immediately behind each of the 75 pockets and these drawers are slidably mounted in the counter, riding upon the ball bearings as indicated. The sliding strip which in the two different forms of my device, as I have indicated, rests upon the upper edge of the back partition or panel wall and either contacts or lies upon the upper edge of the transparent glass window by its presence closes the space at the top of the pocket and protects the material therein 80 against dust and dirt or any deterioration which might arrive where the objects are materially uncovered or exposed.

I claim:

1. A display pocket for counters comprising a rectangular casing, a transparent wall located therein and means independent of material in the casing for holding said wall in position, said means comprising a strip slidably mounted in the casing and engaging 90 said wall, and means for holding said strip removably in position.

2. A display pocket for counters comprising a rectangular casing having a grooved bottom, a transparent wall in said groove 100 and means independent of objects in said pocket for holding said wall in position, said means comprising a strip in opposition to said wall, said strip being slidable in the casing and means for removably holding it 105 in position.

3. A display pocket for counters comprising a rectangular casing, a transparent panel slidably mounted in said casing and means comprising a removable strip 110 slidable itself in the casing and separate from the casing for holding the panel against slidable displacement.
